UNITED STATES PATENT OFFICE.

WILLIAM C. HOMAN, OF MERIDEN, CONNECTICUT, ASSIGNOR TO EDWARD MILLER & COMPANY, OF SAME PLACE.

SUSPENSION DEVICE FOR LAMPS.

SPECIFICATION forming part of Letters Patent No. 408,107, dated July 30, 1889.

Application filed April 1, 1889. Serial No. 305,536. (No model.)

To all whom it may concern:

Be it known that I, WILLIAM C. HOMAN, of Meriden, in the county of New Haven and State of Connecticut, have invented a new 5 Improvement in Suspension Devices for Lamps, &c.; and I do hereby declare the following, when taken in connection with the accompanying drawings and the letters of reference marked thereon, to be a full, clear, 10 and exact description of the same, and which said drawings constitute part of this specification, and represent, in—

Figure 1, a side view of the fixture carrying a lamp-supporting harp; Fig. 2, a top view 15 of the suspension device, a portion of the auxiliary frame broken away for convenience of illustration, enlarged; Fig. 3, a side view of the principal and auxiliary frame, showing vertical section of the spring-drum and 20 dog, a portion of the frame broken away; Fig. 4, a sectional side view, cutting at right angles to Fig. 3; Figs. 5, 6, and 7, modifications.

This invention relates to an improvement 25 in that class of devices for suspending lamps from the ceiling, in which a spring-drum is employed, arranged upon an axis, with two or more chains or cords wound upon the said drum under the reaction of the spring, the 30 lamp, or whatever it may be, attached to said chains, so that drawing down the lamp will impart rotation to the drum to wind the spring, and then the reaction of the spring aids in raising the lamp or thing suspended.

As the variation in weight of the thing 35 suspended is very great, and it is impractical to construct the suspending devices so that the power of the spring of the same fixture will be adapted to such varying weight of 40 things suspended, some device is necessary which will engage the spring-drum and prevent its rotation, except when it is desired to raise or lower the thing suspended, for without such provision the spring-drum, being 45 constructed with a power to support a given weight, if that weight be heavier, would not be able to hold the thing suspended at any other elevation than its lowest point; or, on the contrary, if the thing suspended be much 50 lighter than the power of the spring, then the thing so suspended could be held only

at its highest point of elevation; hence the necessity of some auxiliary power or engaging device upon the drum which will hold it to prevent its rotation except at times when 55 the adjustment is desirable, and at any point within the range of the vertical adjustability.

The object of my invention is to provide a locking device for the drum, whereby it may 60 be rigidly held at any point to which the adjustment may be made, so as to prevent the possible reaction of the spring to draw up the thing suspended, but yet permit easy 65 disengagement, so that the power of the spring may be brought into action to lift or aid in lifting the thing suspended.

To this end the invention consists, principally, in hanging the frame of the spring-drum upon an axis at right angles to the axis 70 on which the drum revolves, and so that a rocking movement may be imparted to said drum, combined with a dog eccentrically arranged about the axis of the drum, the drum provided with a corresponding bearing-surface, 75 with which said dog is adapted to engage when thrown outward by its eccentricity, or from which it may be relieved as the dog is withdrawn from such engagement by such eccentricity, the said rocking movement of 80 the drum and a spring being adapted to throw the said dog into and out of engagement with said drum, and as more fully hereinafter described.

A represents the frame, which carries a 85 vertical axis B, on which the spring-drum C is arranged, as usual in this class of fixtures; D, the suspending-loop by which the fixture may be hung to the ceiling, or wherever it may be desirable. This loop is attached to 90 or formed as a part of an auxiliary frame E, which frame extends down each side the drum.

The frame A is hung to the auxiliary frame E upon pivots F, diametrically opposite each 95 other and at right angles to the plane of the axis upon which the drum revolves. These pivots F should be near the lower end of the drum. Upon the upper head of the drum a concentric flange G is formed. The axle B 100 extends upward and terminates above the drum in an eccentric projection or trunnion

H. Upon this eccentric H a dog I is hung, projecting radially outward toward the flange G, as seen in Fig. 2. A spring J is applied between the frame A and the dog, the tendency of which is to turn the dog upon its eccentric H in the direction to withdraw its nose from engagement with the flange G, as represented in Fig. 2, but yet permit the dog to be turned on its eccentric to give it an outward or radial movement to bring its nose into engagement with the flange G, as represented in broken lines, Fig. 2.

As here represented, the frame A is constructed with uprights K L, on which pulleys M are arranged, over which chains or cords applied to the drum run in the usual manner to the thing to be suspended, these pulleys serving as guides for the proper laying of the chain upon the drum.

20 The spring J is represented as a torsional spring coiled around the eccentric, one arm in engagement with the dog and the other in engagement with the upright K; but the particular arrangement of the spring is immaterial, it only being essential that there shall be a spring, the tendency of which is to throw the dog out of engagement with the drum.

25 The rotation of the drum under the reaction of the spring—that is, in winding the chains onto the drum—is in the direction of the arrow indicated in Fig. 2, when the dog is thrown outward, so as to engage the flange G. Under such engagement the tendency of the spring under reaction is to turn the dog 30 in the same direction as the drum is revolving; but because of the eccentricity of the dog with relation to the axis of the drum the dog can only turn until a positively-forced engagement is made between the drum and 35 the dog. Then further reaction will be prevented, because of the cramp-like action of the dog upon the drum. Consequently, in such position the drum will stand and hold the dog in engagement; but if the drum be rotated in the opposite direction, as by pulling 40 down the thing suspended, the dog will accordingly return until disengaged from the drum. Then the spring J of the dog operates 45 to throw the dog to its positively disengaged position, as represented in Fig. 2.

50 The auxiliary frame E is provided with two downwardly-projecting studs N O, which extend down opposite sides of the dog I. The dog is constructed with a shoulder P on one 55 side, corresponding to the stud N of the frame E, and upon the opposite side the dog is constructed with a like shoulder R, corresponding to the stud O on the frame E, these shoulders P R of the dog being upon opposite sides 60 of their respective pins and on the side in opposition to the action of the dog-spring, so that the said studs N O form stops against which the dog will be brought under the action of its own spring when disengaged from the drum, as before described and as seen in 65 Fig. 2. This completes the construction.

The operation is as follows: Suppose the

drum to stand in its horizontal position, as seen in Fig. 1, with the dog held back against its stops and out of engagement with the 70 drum, as represented in Fig. 2. Now the spring-drum is free to rotate in either direction, so that the thing suspended may be drawn down or raised, as may be desirable; but when the desired position is attained, to 75 engage the drum in that position, so as to insure the thing suspended remaining at that point, the drum is turned upon its pivots F F, so as to bring it to the inclined position, as represented in broken lines, Figs. 1 and 4. 80 Under this operation the auxiliary frame E does not move. The studs O N consequently remain stationary, but the dog rocks with the drum, and as such rocking of the drum throws the eccentric to one side or the other, according to the direction in which the rocking is produced, it necessarily follows that the stop on the frame E will operate against the corresponding shoulder of the dog I and turn it accordingly, and as the shoulders of 90 the dog are upon that side of the stops in the direction in which the dog must turn to be engaged with the drum, it follows that under such swinging movement the dog will be turned upon its eccentric, as indicated in 95 broken lines, Fig. 2, and until its nose is brought into engagement with the flange of the drum. When the dog is in such position for engagement, the pulling down of the thing suspended causes a rotation of the 100 drum in the direction opposite to the arrow, Fig. 2, the dog readily yielding for such rotation without substantially opposing the movement of the drum; but as soon as the force which was pulling down is removed then the 105 reaction of the spring-drum tends to turn the drum in the direction of the arrow, Fig. 2, and to force the engagement with the dog. Consequently the dog produces a cramp upon the drum, and so long as that cramp is maintained the reaction of the spring of the drum is prevented, and while the dog is thus engaged the spring-drum may be brought back to its horizontal position, and there remains, 110 suspending the lamp or thing at the point to 115 which it may have been adjusted, as described.

To release the engagement of the dog with the drum so as to permit the reaction of the spring, a slight pull down upon the chains will turn the drum in the direction opposite to that of the reactive force of the spring, and with it the dog. The dog, turning upon its eccentric, is withdrawn from its engagement with the drum, and as soon as it is free 120 from such engagement the reactive force of the spring J throws the dog backward against its stops and out of engagement with the drum, so that now the drum is free to rotate in either direction for readjustment of the 125 thing suspended, and when such readjusted position is attained the drum and its frame are rocked again, as before, to bring the dog into engagement to lock the drum.

I represent the dog as making frictional engagement with the flange; but it will be understood that any of the known equivalents for a friction-dog to operate upon the drum 5 may be employed—as, for illustration, a pawl and ratchet, the pawl being hung upon the frame, as seen in Fig. 5; but so that the stops, under the rocking movement of the drum, will bring the pawl into engagement with the

10 ratchet, as indicated in broken lines, Fig. 5. This simple illustration, as one known equivalent for the dog, will be sufficient to enable others skilled in the art to apply other known equivalents.

15 As a convenient means for imparting the rocking movement to the drum, the harp of the lamp-frame is constructed with its two sides *S* *T* hinged to opposite sides of the fount-support *U*, as at *a a*, Fig. 1. These sides *T* ex-

20 tend upward and are connected to an evener *b*, the two chains *d* from the drum being connected to the same eveners at the two points above. Now when it is desired to give the rocking movement to the drum for the purpose of 25 making the engagement before described, one side of the harp is pulled downward, as indicated in broken lines, Fig. 1, which imparts corresponding movement to the evener *b* and corresponding rise to the opposite side *S* of

30 the harp. This movement operates upon the drum-frame through the chains and correspondingly turns the drum upon its pivots, as also indicated in broken lines, Fig. 1. Because of hinging the two sides of the harp to

35 the fount-support and the introduction of the evener between the drum-chains, this up-and-down movement may be produced from either side of the harp, and when free the natural gravity of the parts will bring the frame back 40 to its normal position and so that the fount will hang horizontally. The rocking movement of the drum, however, may be otherwise imparted—say in cases where the lamp or thing suspended is hung to a hook centrally

45 between the chains, as in Fig. 6, a cord or chain *f* may be arranged extending downward within convenient reach, by the pulling of which the inclination of the drum will be produced, as indicated in Fig. 6. In this case, 50 the suspension being central between the chains, the drum will naturally turn to its horizontal position when free so to do.

I represent the dog as constructed with two shoulders and the auxiliary frame with two 55 corresponding bearing-points. This permits the drum to be rocked in either direction, with the same result of locking the drum; but one such engagement may be omitted, the other being sufficient, except that the engagement 60 will be made only from one side—that is, by rocking the drum in one direction only.

In some cases it may be desirable to hold the drum constantly locked, and so as to be unlocked by the rocking movement of the 65 drum, instead of holding the drum unlocked and locking it by the rocking movement, as described. In such case it is simply a revers-

ing of the operation of the dog, as seen in Fig. 7, the dog being in the engaged position normally and disengaged by the rocking of 70 the drum, as indicated in broken lines, same figure. In the latter case the disengagement is produced by the rocking of the drum in the opposite direction to that in the first illustration.

75

I claim—

1. In a suspension device for lamps and like purposes, the combination of a principal frame, a spring-drum hung upon an axle in said principal frame, an auxiliary frame by 80 which the said device is adapted to be suspended, the said principal frame hung to the auxiliary frame upon an axis at right angles to the axis upon which the drum revolves, and whereby the said drum and its axle are permitted a rocking movement, and an engaging device between said auxiliary frame and the said drum, substantially as described, whereby under such rocking movement of the drum the said engaging device is brought into action 85 with the drum to prevent the reactive force of the spring-drum.

2. In a suspension device for lamps and other articles, the combination of a principal drum, an axle stationary in said frame, a spring- 95 drum arranged to revolve upon said axle, the axle extending through the drum and constructed at its projecting end with an eccentric, an auxiliary frame to which the principal frame is pivoted upon an axis at right angles 100 to the axis upon which the drum revolves, the said auxiliary frame serving as a means for suspending the device, the head of the drum around the eccentric end of the axle constructed with a concentric engaging-surface, 105 a locking-dog between said engaging-surface and said eccentric, the said locking-dog constructed with one or more shoulders, and the auxiliary frame with bearing-points corresponding to said shoulder or shoulders, and 110 with which points said shoulders are adapted to engage under a rocking movement imparted to said drum, with a spring arranged to yieldingly hold the said dog out of engagement with the drum, substantially as described.

3. The combination of the principal frame *A*, carrying a stationary axle *B*, the spring-drum *C*, hung upon said axle, the axle extending through the drum and terminating above in an eccentric *H*, an auxiliary frame *E*, hung 120 to said principal frame upon pivots forming an axis upon which the said drum may swing at right angles to the axis upon which the drum revolves, a dog *I*, hung upon said eccentric *H*, the end of the drum constructed with 125 a concentric flange *G*, within which said dog is arranged, the dog constructed with one or more shoulders, and the auxiliary frame with corresponding bearing-points with which said shoulders of the dog are adapted to engage as 130 the drum is rocked, with a spring applied to said dog, the reactive force of which is adapted to hold the said dog yieldingly out of engagement with the drum, but permit its

engagement with the drum under a rocking movement of the drum, substantially as described.

4. The combination of a frame provided with an axle, a spring-drum arranged to revolve on said axle, an auxiliary frame by which the said drum may be suspended, the frame of the drum hung to the said auxiliary frame on an axis at right angles to the axis on which the drum revolves, and whereby the drum is permitted a rocking movement at right angles to the axis of its revolution, an engaging device between the said drum and auxiliary frame adapted to interlock with the drum under such rocking movement, two chains running from said drum downward, an evener constructed with two points of connection, and to which said chains are attached, and the evener constructed with two other points of connection below said two-chain points of connection, and a harp for suspending a lamp composed of two sides and a fountain, the said two sides hinged to the said fountain and, extending upward, attached to the said two other points on the evener, substantially as described.

5. The combination of a frame provided with an axle, a spring-drum arranged to revolve on said axle, an auxiliary frame by which the said drum may be suspended, the frame of the drum

hung to the said auxiliary frame, and whereby the drum is permitted a rocking movement at right angles to the axis of its revolution, an engaging device between the said drum and auxiliary frame adapted to interlock with the drum under such rocking movement, two chains running from said drum downward, an evener constructed with two points of connection, and to which said chains are attached, and the evener constructed with two other points of connection below said two-chain points of connection, and a harp for suspending a lamp composed of two sides and a fountain, the said two sides hinged to the said fountain and, extending upward, attached to the said two other points on the evener, substantially as described.
